his Attorney.

UNITED STATES PATENT OFFICE.

ROBERT S. MANUS, OF CLEVELAND, OHIO, ASSIGNOR TO THE MANUS CANDY COMPANY, OF CLEVELAND, OHIO, A CORPORATION OF OHIO.

DESIGN FOR A BAR OR CAKE OF CANDY OR CONFECTIONERY.

53,422.

Specification for Design.

Patented June 10, 1919.

Application filed February 21, 1919. Serial No. 278,550. Term of patent 14 years.

To all whom it may concern:

Be it known that I, ROBERT S. MANUS, a citizen of the United States, residing at Cleveland, in the county of Cuyahoga and State of Ohio, have invented a new, original, and ornamental Design for a Bar or Cake of Candy or Confectionery, of which the following is a specification, reference being had to the accompanying drawing, forming part thereof.

Said drawing is a perspective view of a bar or cake of candy or confectionery showing my new design.

I claim:

The ornamental design for a bar or cake of candy or confectionery substantially as shown.

ROBERT S. MANUS.

Witnesses:

LOUIS B. SPANNER,
W. H. McDONNELL.
